UNITED STATES PATENT OFFICE.

BERNHARD DREYFUS, OF NEW YORK, N. Y.

DESIGN FOR A PENDANT.

SPECIFICATION forming part of Design No. 14,567, dated January 29, 1884.

Application filed November 22, 1883. Term of patent 14 years.

To all whom it may concern:

Be it known that I, BERNHARD DREYFUS, of the city, county, and State of New York, have invented and produced a new Design for Pendants, of which the following is a full, clear, and exact description.

Reference is to be had to the accompanying drawings, forming a part of this specification, in which a longitudinal view of my newly-de-

signed pendant is shown.

The pendant A is made in the shape of an ellipse, having both ends pointed. From the lower end of the pendant a small ball or bead, B, is suspended, and to the upper end of the pendant a ball or tuft, C, is fastened, to which a loop, D, is secured. A collar, E, formed of loops or like configurations, is formed around the upper end of the pendant. The outer surface of the pendant is of fuzzy nature.

Having thus described my design, I claim as new—

1. The herein-described newly-designed pendant, made in the shape of a pointed ellipse, as shown.

25 2. The herein-described newly-designed

pendant, consisting of a pendant made in the shape of a pointed ellipse, and having a bead or ball suspended from its lower end, as shown.

3. The herein-described newly-designed pendant, consisting of a pendant made in the shape of a pointed ellipse, from the lower end of which a ball or bead is suspended, and to the upper end of which pendant a ball or tuft is secured, as shown.

4. The herein-described newly-designed pendant, consisting of a pendant made in the shape of a pointed ellipse, having a bead or ball suspended from the lower end and a ball or tuft at the upper end, and a collar surrounding the top of the pendant, as shown.

5. The herein-described newly-designed pendant, consisting of a pendant made in the shape of a pointed ellipse, having a ball or bead at the lower end, a ball or tuft and a loop at the upper end, as herein shown.

BERNHARD DREYFUS.
